INSTRUMENT PANEL FOR A STERILIZER

Sherman B. Campbell, Erie, Pa., Charles F. Stephenson, New York, N.Y., and Raymond Spilman, Darien, Conn., assignors to American Sterilizer Company, Erie, Pa., a corporation of Pennsylvania

Continuation of design applications Ser. No. 87,548, Oct. 18, 1965, and Ser. No. 87,591, Oct. 19, 1965. This application Oct. 31, 1966, Ser. No. 5,621

Term of patent 14 years

(Cl. D83—1)

Des. 209,560

PAGE 3

Fig. 2

Fig. 3

Fig. 4

FIG. 1 is an isometric view of an instrument panel for a sterilizer, showing our new design, the dominant features reside in the portions shown in full lines;

FIG. 2 is a side elevational view thereof;

FIG. 3 is an isometric view of another embodiment of the instrument panel for a sterilizer, showing our new design, the dominant features reside in the portions shown in full lines; and

FIG. 4 is a side elevational view of the instrument panel for a sterilizer shown in FIG. 3.

The lines illustrating the sterilizer door are shown for illustrative purposes only.

This is a continuation of application Serial Numbers D. 87,548, filed Oct. 18, 1965 and D. 87,591, filed Oct. 19, 1965, and both now abandoned.

We claim:

The ornamental design for an instrument panel for a sterilizer, as shown and described.
